(57) **CLAIM**

The ornamental design for a tablet enclosure credit card reader, as shown and described.

DESCRIPTION

FIG. 1 is a top plan view of a tablet enclosure credit card reader;

FIG. 2 is a front elevational view thereof;

FIG. 3 is a bottom view thereof;

FIG. 4 is a left elevational view thereof;

FIG. 5 is a rear elevational view thereof;

FIG. 6 is a right elevational view thereof;

FIG. 7 is a left-front isometric view thereof;

FIG. 8 is a right-front isometric view thereof;

FIG. 9 is a left-front isometric view thereof, showing our design mounted to a pyramid swivel base assembly; and,

FIG. 10 a left-rear isometric view thereof, showing our design mounted to a pyramid swivel base assembly.

The broken lines are for environmental purposes only and form no part of the claimed design.

The claimed tablet enclosure credit card reader is used to process credit cards.
